ELECTRIC HAIR CLIPPER

Filed Jan. 9, 1931

UNITED STATES PATENT OFFICE

GESUALDO C. SIRECI, OF BROOKLYN, NEW YORK

ELECTRIC HAIR CLIPPER

Application filed January 9, 1931. Serial No. 507,727.

This invention appertains to clippers of the type particularly adapted for use in tonsorial establishments.

One of the primary objects of my invention is to provide a novel electrically driven hair clipper, in which the blades extend parallel with the longitudinal axis of the handle whereby the clipper can be readily manipulated for effectively bringing about the proper trimming of the hair.

Another important object of my invention is the provision of electrically driven hair clippers in which the blades project forwardly of the handle and parallel with the longitudinal axis thereof, whereby the teeth of the blades can be readily used as a comb incident to the cutting of the hair.

A further salient object of my invention is the provision of novel means for forming the handle and novel means for arranging the gearing for the reciprocating blade within the handle, the device embodying a minimum number of operating parts, all of which are readily accessible to permit adjustment, repair, and the like.

A further important object of my invention is the provision of novel means for arranging the reciprocating blade on the stationary blade or guard plate and relative to the cap plate, with novel means for regulating the tension between the reciprocating blade and the guard or stationary blade.

A still further object of my invention is to provide electrically driven hair clippers of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawing, in which drawing:

Figure 1 is a side elevation of my improved hair clippers.

Figure 2 is a top plan view thereof with the flexible driving shaft disconnected therefrom.

Figure 3 is a transverse section through the cutting blade taken on the line 3-3 of Figure 1 looking in the direction of the arrows.

Figure 4 is a top plan view of the improved clippers with the cap plate removed and parts of the device broken away and in section.

Figure 5 is a central longitudinal section through the improved clippers.

Figure 6 is a detail perspective view of the stationary blade or guard plate with the gear box connected therewith.

Figure 7 is a detail perspective view of the reciprocating blade, and

Figure 8 is a detail perspective view of the cap plate.

Referring to the drawing in detail, wherein similar reference characters designate corresponding parts throughout the several views, the letter A generally indicates my improved hair clippers, which comprise the forwardly projecting stationary blade or guard plate 10, having formed on the rear end thereof the housing 11, which embodies the bottom wall 12, and the upstanding side walls 13 and 14. These side walls 13 and 14 have their forward ends arcuated or curved downwardly toward the stationary blade or guard plate 10, as clearly shown in Figures 1 and 6.

The side walls 13 and 14 and the bottom wall 12 are connected together by a rear wall 15, having the arcuate notch 16 formed therein for a purpose which will be later described.

One longitudinal edge of the stationary blade or guard plate 10 is provided with a plurality of cutting teeth 17. From the construction so far, it is to be noted that the stationary blade or guard plate 10 projects forwardly from the housing 11 and is parallel with the longitudinal axis thereof. The upper face of the stationary blade of guard plate 10 is provided with a longitudinally extending groove 18, defining a longitudinally extending rib 19 at the rear edge of the plate or stationary blade and this rib is provided with a longitudinally extending guide groove 20.

Reciprocately mounted upon the guard plate or stationary blade 10 is the movable cutting blade 21 having formed upon one

longitudinal edge thereof the cutting teeth 22, which cooperate with the teeth 17 for clipping the hair during the reciprocation of the movable blade. The inner face of the blade 21 is 5 also preferably provided with a relatively wide groove 23, and the rear edge of the blade is provided with a rib 24 for bearing engagement with the rib 19, and is provided at spaced points with guide tongues 25 for reception in the guide groove 20. The inner edge of the blade 21 is provided with a rounded slot or notch 26, which forms a bearing, for a purpose which will be later brought out.

Extending longitudinally of the movable 15 blade is a slot 27 through which is adapted to extend the holding screw 28, the screw being placed through the stationary blade 10 through a suitable opening 29. The head of the screw can be countersunk within the 20 lower face of the stationary blade.

In order to hold the reciprocating blade in proper position on the stationary blade and to guide the same during its movement, I provide a head or cap plate 30, having the longitudinally extending ribs 31 and 32 on its front and rear edges. The rear rib 32 can be provided with a depending tongue 33 for engaging over the rear edge of the reciprocating blade, while the front rib 32 can be notched at suitable points as at 34 and rests upon the top surface of the blade. The holding screw 28 extends through an opening 35 in the said head or top plate 30, and has threaded thereon a thumb nut 36. A tension spring 37 is coiled about the bolt 28 and is confined between the thumb nut 36 and the head or cap plate 30. It is obvious that by tightening or loosening the thumb nut 36 that the tension of the spring 37 can be adjusted, thereby bringing about the adjustment of the movable blade 21 relative to the stationary blade 10.

The housing 11 is adapted to receive a suitable bearing or casting 40, for the rotatable 45 drive shaft 41. This bearing or casting 40 can be held in place within the housing 11 by means of suitable screws 42 or the like. This shaft is adapted to have connected therewith in any preferred way, a flexible drive shaft 50 43, which can be driven from any preferred type of motor (not shown). The bearing or casting 40 carries a threaded sleeve 44, through which the drive shaft 41 extends, and a head nut 45 can be threaded on the said 55 sleeve around the flexible shaft 43. A set screw 46 can be employed for holding the head nut 45 against accidental rotation. The inner end of the drive shaft 41 has secured thereto, in any desired way, a bevel drive gear 60 47, which meshes with a similar bevel gear 48, formed on or secured to an eccentric cam 49. A holding bolt or shaft 50 extends axially through the gear 48 and eccentrically through the cam 49 and this bolt likewise extends 65 through the bottom wall 12 of the housing 11,

for a purpose which will be later described. It is to be noted, however, that upon rotation of the drive shaft 41 that the bevel gear 48 and consequently the eccentric cam 49 will be rotated. This cam is received within an eccentric strap 51 formed on the inner end of a pitman rod or the like 52. The forward end of the pitman is provided with a rounded head 53, which fits within the rounded socket 26 in the movable blade 21. Thus, upon rotation of the cam 49 the pitman 52 will reciprocate the movable blade 21.

I provide a cover plate 55 for the housing 11 and this cover plate embodies a top wall 56 and a forwardly and downwardly extending front wall 57 and the cover plate is adapted to snugly engage the edges of the side walls 13 and 14 and the rear wall 15. Suitable gaskets can be interposed between the meeting surfaces of the cover plate 55 and the side 55 and rear walls of the housing, so as to absorb any shock and to reduce vibration and prevent the leakage of any grease between the cover plate and the walls of the housing. The front edge of the cover plate can be notched as at 58 to permit the pitman rod to extend therethrough and under the cap plate 30.

The bolt or shaft 50 extends through the cover plate 55 and a winged or thumb nut 59 can be threaded on the bolt or shaft in engagement with the cover plate. Thus the bolt or shaft 50 is employed for the dual purpose of connecting the cover plate with the housing, and for rotatably supporting the bevel gear 48 and the eccentric cam 49.

From the foregoing description, it can be seen that I have provided a novel hair clipper which is of an exceptionally simple and durable construction and in which the cutting blade is arranged parallel of the longitudinal axis of the gear housing or handle, whereby the cutting teeth will be arranged at one longitudinal edge of the device.

Changes in details may be made without departing from the spirit or the scope of this invention, but:—

What I claim as new is:

In a hair clipper device, a housing having bottom, side and rear end walls, the bottom wall being formed with a continuation defining a guard plate, said rear wall being formed with a recess opening out through the upper edge thereof, a bearing in said recess, a shaft extending through said bearing and having a gear on the forward portion thereof, a combined bolt and spindle carried by said bottom wall and having a fastening element, a cam mounted on the combined bolt and spindle and having a beveled gear meshing with said first named gear, a cover plate extending over said bearing, said first and second named beveled gears and resting on the upper edges of said side walls, said cover plate being formed with an opening extending out through the upper surface thereof for

the full passage of said combined bolt and spindle, said fastening element being engaged with the top of said cover plate and being removable to allow of the removal of the cover plate without disturbing the beveled gears, the combined bolt and spindle or said cam, a movable blade mounted for reciprocation on the guard plate, a stationary cap plate engaging the movable plate, a pitman rod connecting the movable blade and the cam, said cover plate being provided with a notch formed in the outer lower end thereof for the passage of said pitman rod.

In testimony whereof I affix my signature.

GESUALDO C. SIRECI.
